Term of patent 14 years

(Cl. D33—8)

FIG. 2

FIG. 3

To all whom it may concern:

Be it known that I, William P. Crockett, Jr., a citizen of the United States, residing at Chicago, State of Illinois, have invented a new, original, and ornamental Design for a Combined Valet Stand and Garment Hanger, of which the following is a specification, reference being had to the accompanying drawings forming a part thereof.

Fig. 1 is a perspective view of a combined valet stand and garment hanger showing my design;

Fig. 2 is a front elevation thereof, the garment hanger element being omitted; and

Fig. 3 is a side elevation thereof, the opposite side being identical thereto, the garment hanger element being omitted.

The dominant features of my design reside in the portions shown in full lines.

I claim:

The ornamental design for a combined valet stand and garment hanger, as shown and described.
